UNITED STATES PATENT OFFICE

2,419,497

MULTIPLE CELL FLOTATION APPARATUS
INCLUDING RECYCLING MEANS

Stephen E. Meyer, Hayden, Ariz.

Application October 30, 1943, Serial No. 508,287

2 Claims. (Cl. 209—168)

1

This invention is an improvement on the subject matter of my former patent application Serial No. 369,485, filed December 10, 1940, and relates to new and useful improvements in flotation method and apparatus for recovering minerals such as gold, silver, and copper from their ores.

The principal object of the present invention is to provide a flotation system wherein the finished high-grade concentrates are returned in part to the original feed head in a manner to build up therein an artificial higher head whereby a much higher grade concentrate is obtained without resort to certain operations now required to be performed following the flotation operations, to obtain sufficiently high-grade concentrate.

Other objects and advantages of the invention will become apparent to the reader of the following specification.

In the drawings:

Figure 1 represents a diagrammatic view disclosing the various connections between the units involved.

Figure 2 is a longitudinal sectional view through one of the machines which forms the subject matter of my Patent No. 1,722,705, issued July 30, 1929.

Figure 3 is a fragmentary sectional view taken substantially on line 3—3 of Figure 1.

Figure 4 is a sectional view taken substantially on line 4—4 of Figure 3.

Referring to the drawings wherein like numerals designate like parts, it can be seen that Figures 2, 3 and 4 are representative of the subject matter of my patent No. 1,722,705, issued July 30, 1929. These patented flotation machines are used in the system of the present invention and are denoted generally by reference characters A, B and C. The machine identified as the cleaner in Figure 1 and generally referred to by the letter D is of like construction. Each of the machines A, B, C and D consists of a casing including a bottom 5, sides 6 and end walls 7 and 8. A partition 9 forms with the end wall 7 and has an entrance 10 for feed. A partition 11 forms with the end wall 8 and has an exit 12. Longitudinally extending walls 14 are disposed between partitions 9 and 11 for forming an aerator space therebetween. The aerator is supported on legs 16 rising from the bottom 5. Numeral 20 denotes a main air header manifold which has air pipes 25 rising therefrom. A closed casing 24 forms part of the aerator and has a plurality of slots 38 in the lower portion thereof.

2

5 A screen 36 extends across the upper edges of the walls 14 and casing 24 extends through openings therein. Pipes 17 extend upwardly from the bottom of the casing 24 through the top thereof and have caps 17' closing the upper ends of the pipes 17. The pipes 25 extend up through the bottom of the casing 24 and terminate interiorly of the pipe 17 adjacent the top of the casing 24. Walls 33 extend between partitions 9 and 11 in parallel 10 spaced relation, being spaced farther apart than walls 14 and being disposed above the walls 14. These walls form froth-retarders. An overflow gate 35 is mounted in the guide 2 on the side wall 6 between end wall 8 and partition 11. This gate 15 may be adjusted vertically to properly adjust the feed level of the machine. Numeral 30' denotes the slots in the lower ends of the pipes 17. Numeral 40 denotes a control valve in the air header. An outlet 43 is provided in the lower portion of 20 the end wall 8 for the tailings from the machine, the usual launder trough 44 being provided on the outer sides of the side wall 6, and said side walls 6 are provided with openings 45 leading into the launder troughs 44.

25 In carrying out the present invention utilizing the patented machine above briefly described, it can be seen that numeral 50 denotes a pump sump to which extends the feed line or feed head 51. In communication with the sump 50 is a 30 pump 52 driven by an electric motor 53. From the pump 52 extends a conduit 54 to a distributing tub 55. From the tub 55 conduits 56, 57 and 58 extend to the machines A, B and C. In this manner feed is made to the machines A, B and C. From the machine pipes 59, 60 and 61 extend 35 and connect to a common pipe 62 for the carrying off of tails.

As can be seen in Figure 1, pipes 63 communicate the launders of the different flotation machines, the machine C having a portion of each 40 of its launders 44 partitioned off, as at 64, to define the small launders 65 from which concentrates are removed by way of the pipes 66 and 67 and lead to the cleaner machine D. In 45 this machine, which is constructed in accordance with the subject matter of my patent No. 1,722,705, issued July 30, 1929, the concentrate is removed from the launders 44 thereof and lead to a suitable receiver by way of conduits 68. Cleaner tails from the machine D pass through conduits 69 to a sump 50.

The pipes 63 communicating the launders and the outside launders 44 of the end machines A and C are connected by return pipes 70, 71, 72 and 73 to the pump sump 50.

In accordance with the present invention, most of the finished concentrate is conveyed to the pump sump to form and maintain therein an artificially higher head. The amount of finished concentrate returned to the sump depends upon the grade of concentrate desired, and a skilled attendant will readily regulate this amount until the desired artificial higher head has been obtained and the desired grade of concentrate is produced. The remaining smaller fraction of finished, high-grade concentrate is discharged from the machine C by way of the pipes 66 and 67 which form the only outlet of the system. In this manner a higher finished grade concentrate is obtained without resort to the additional operations and machines now necessary to obtain ordinary high-grade concentrate.

As can be seen in Figure 1, the concentrate lead-off pipe 68 has a branch 68a which returns some of the concentrate from the cleaner cell to the pump sump 50. There is a marked advantage in returning a percentage of the concentrate to the pump sump. A drier cake from the filter plant results. This is because the flow eliminates a large part of the colloidal slimes which hamper the filtering of concentrate. The result of having a drier cake means to the smelter less oil or gas to roast them dry before going to the furnace. Further, there is less tonnage in transportation from filter plant to smelter than from there to its destination in the form of freight.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a flotation apparatus of the character described, the combination of a plurality of at least three flotation machines, each having launders and a feed entrance and a tailings exit, a first one of said flotation machines having each of its launders divided into two compartments, a sump, a froth feed head discharging into said sump, a distributing tub, means for pumping the froth from said sump to said distributing tub, means to convey the froth from said tub to the

entrances of all but a second one of said flotation machines, means to convey concentrate from the launders of a third one of said machines and from corresponding launder compartments of the first one thereof to said sump, means to convey concentrate from the other launder compartments of the first one of said machines to the feed entrance of the second one of said machines, means to convey tailings from the exit 10 of the second one of said machines to the sump, means to convey the tailings from the exits of the first and third machines away from the apparatus, and means to convey concentrate from the launders of the second machine away from the apparatus.

2. In a flotation apparatus of the character described, the combination of a plurality of at least three flotation machines, each having launders and a feed entrance and a tailing exit, a first one 20 of said flotation machines having each of its launders divided into two compartments, a sump, a froth feed head discharging into said sump, a distributing tub, means for pumping the froth from said sump to said distributing tub, means to 25 convey the froth from said tub to the entrances of all but a second one of said flotation machines, means to convey concentrate from the launders of a third one of said machines and from corresponding launder compartments of the first one thereof to said sump, means to convey concentrate from the other launder compartments of the first one thereof to said sump, means to convey concentrate from the launders of the second machine away from the apparatus and part thereof to the sump.
